UNITED STATES PATENT OFFICE

2,463,126

RADIUS-ANGLE FORMER

Ingolf Snea, Bedford, Ind., assignor to W. F. Meyers Company, Bedford, Ind., a corporation

Application January 30, 1946, Serial No. 644,263

11 Claims. (Cl. 125—11)

1

This invention relates to an apparatus for dressing grinding wheels through the usual application thereto of a diamond dressing tool, as well as the forming of tools by precise grinding when applied to a plain surface grinding wheel, reference being had to my Letters Patent No. 2,436,873, granted March 2, 1948, entitled "Radius-angle tool former."

More particularly, the former herein disclosed is adapted on the one hand to support a diamond dressing tool and so apply it to the dressing of a grinding wheel as to dress said wheel to any desired angle, radius of curvature or angle tangent to a prescribed radius to curvature. On the other hand, a tool to be formed may be substituted on this former in place of the diamond dressing tool, and similarly applied thereby to a grinding wheel for grinding any prescribed angle, radius of curvature or angle tangent to radius as may be desired.

The principal object of this invention is to provide an accurate and convenient locating device for determining the location of the tool in relation to the line intersecting the axis of rotation of the former without the use of manually positioned or operable stop devices. This is accomplished by provision of a suitable camming device mounted upon one of the compound slides positioned for engagement with mechanism upon the other of the compound slides for actuating a visual range indicator.

A feature of the invention resides in the double angle cam in operative association with an actuating bell crank lever of such ratio as to enable direct readings of the relative movements between the slides in only one thousandth of an inch in either direction from center over a distance of movement of as much as two inches with a one inch range indicator.

Another feature of the invention resides in the construction and mounting of the operating lever for protection thereof from dust and grit resulting from the grinding operations.

One of the advantages of the visual indicator control in respect to the centering of the compound slides and the distance of movement or positioning of the tool relative to the line intersecting the axis of rotation of said slides, results from the minimum wear of the locating device or indicator operating mechanism, such as to effect the precision of the instrument, and also eliminating the "feel" of the operator otherwise required in locating the tool through the use of stop blocks or pins. Since, in the use of this invention there is a minimum of wear, the

2

precision locating and setting of the tool is governed by the precise accuracy of the range indicator.

The full nature of the invention will be understood from the accompanying drawings and the following description and claims:

Fig. 1 is a perspective view showing the former mounting and diamond wheel dresser with dust cap removed.

Fig. 2 is a central vertical section through the visual indicator control mechanism with the dust cap in place.

Fig. 3 is an illustrative diagram showing a portion of a grinding wheel being dressed with angles tangent to the radius of curvature.

Fig. 4 is a view similar to Fig. 3 illustrative of a tool being formed by a cupped grinding wheel.

In the drawings there is illustrated a wheel or tool former adapted to be secured in the usual manner to a grinder table in adjustable relation to the usual motor driven grinding wheel 10 to be dressed, as illustrated in Figs. 1 and 3, or the grinding wheel 11 for forming a tool thereby, as illustrated in Fig. 4. The former includes the base 12 adapted to be securely clamped to the grinder table by any suitable means, said base being provided with a V-groove 13 in its bottom surface for receiving a dowel pin 14 for adjusting its angular relation to the horizontal. Said base 12 is provided with a turntable or swivel support 15, both the base and the swivel support carrying an annular Vernier scale, as indicated at 16. Mounted upon the swivel support 15 there is a lower or elongated slide 17 supported upon said swivel support 15 to slide diametrically thereon. Carried on the slide 17 there is an upper or transverse slide 18 which is slidable transversely of the elongated slide. Thus, the slides 17 and 18 provide a compound slide support, the latter carrying a vertically and upwardly extending hollow post 19.

Slidably and adjustably mounted on the post there is a tool holder 20 suitable for supporting and clamping either a tool bit 21 (Fig. 4) engageable to be formed by the cupped grinding wheel 11, or a diamond tool 22, 22a for dressing the grinding wheel 10, as shown in Figs. 1 and 3. Said tool holder is secured to the post 19 at the proper height by a set screw 23.

The upper transverse slide 18 is provided with a rack bar 24 extending transversely along the rear end thereof engageable and operable by a pinion 25 rotatably supported upon the elongated slide 17 and rotatable by operating handle 26. Through manipulation of the handle 26 the rack

and pinion will cause the slide 18 to move transversely of the slide 17. At determined positions of movement the slide 18 may be set and locked in position by a clamping lever 27 mounted thereon and arranged to engage and clamp the slides 17 and 18 to prevent relative movement between said slides.

The elongated slide 17 is similarly adjustable axially of the swivel support 15 through the usual screw shaft operable through a rotatable wheel 28 which carries a Vernier scale 29. Adjustable stop devices, one of which is indicated at 30, are carried by an annular disk 31 secured to the base 12 adjustable about the periphery thereof to limit the swivel movement of the swivel support 15 relative thereto.

Secured to the upper face of the elongated slide 17 adjacent the transverse slide 18 there is a cam supporting block 32 to which the cam plate 33 is rigidly secured. Said cam plate is formed with a pair of opposed camming surfaces 34, 35 tapering inwardly to meet in a V-formation in a precise line extending longitudinally of the elongated slide 17 intersecting its center of rotation. Said camming surfaces face the post 19 and are positioned to be engaged by the arm 36 of a bell crank lever, said arm having a spherical bearing formation 37 on the end thereof. A supporting bracket 38 for said lever is secured upon the upper face of the transverse slide adjacent the cam plate to pivotally support said bell crank lever at 39. The other arm 40 of said lever, which as shown herein is twice the length of the arm 36, extends through a slot 41 in the post 19, terminating in a spherical bearing 42 for supporting the lower end of an extension rod 43.

The extension rod 43 is slidable longitudinally of the hollow post 19, extending upwardly therein to engage a spindle 44 operably connected in the usual manner with an indicator pointer 45. Said spindle is slidable in a barrel 46 extending downwardly into the hollow post and secured therein by a set screw 47 and carries a casing 48 of the usual dial indicator 49. The dial indicator is of a standard type well known in the art, being so designed as to indicate movements of its spindle 44 in the nature of one thousandths of an inch and provide readings throughout a one inch displacement of the spindle. Surrounding the lower end of the post 19 and mounted over the bell crank lever 36, 40, to rest upon the cam plate 33, there is provided a dust guard cap 50 which may be slidable up the post to give access to said plate and bell crank lever.

In operation, through the handle 26, the transverse slide may be reciprocated back and forth across the elongated slide to position or set said transverse slide with the center of the post 19 on a line intersecting the center of rotation of the elongated slide. In this position the bearing end 37 of the bell crank lever is at the innermost V-center of the camming surfaces 34, 35. This is, therefore, the lowermost position of the dial spindle 44 which positions the hand 45 at zero on the dial indicator. Thus, it may be said that when the slide is centered, the dial reads at zero. Upon movement of the transverse slide 18 in either direction away from its center, the bearing 37 of the bell crank lever moves along one or the other camming surfaces 34, 35, correspondingly raising the dial spindle 44. Any ratio of movement desired may be employed, as shown herein the ratio being two to one, wherein the arm 40 of the bell crank lever is twice the length of the arm 36. Thus, for every increment of transverse

movement of the slide 18, there will be half a corresponding movement of the dial spindle. Wherein the dial spindle may be such as to have an inch movement, it will, therefore, in fact indicate two inches of movement in either direction of the slide 18.

The angular relation of the camming surfaces 34 and 35 is such as to transmit the proper dial recording movement of the spindle 44 in accordance with the distance of transverse movement of the slide 18 relative to the slide 17.

By means of the above mechanism, the transverse slide 18 carrying a tool may be accurately centered, indicated by the dial showing zero, or 15 may be moved in either direction or set at any transverse position relative to its center of rotation. The tool may thereby be accurately positioned for dressing a curvature, or located at any position tangential to said curvature for dressing an angle tangent thereto. This is indicated in 20 Fig. 3 wherein the tool is rotated about the axis A while the dial reads zero and may then be moved at an angle tangent thereto as indicated by the tool shown by dotted lines, to a prescribed 25 distance as indicated by the dial. In dressing other forms of wheels, the position of the tool 22 may be set at varying prescribed distances off center according to the reading of the dial.

As illustrated in Fig. 4, a tool 21 may be formed 30 by the wheel 11, the relative position thereof being off center from the center of the post 19 a prescribed distance, as indicated by the dial, and the rotative positions about the center of curvature B being illustrated by dotted lines.

35 The invention claimed is:

1. A radius former comprising a base having a swivel support thereon, a first slide mounted for adjustment diametrically of said support, a second 40 slide mounted for transverse adjustment relative to said first slide, an upright post carried by one of said slides, means for supporting a tool on said post, a visual indicator mounted on said post, and an actuator therefor on the other slide for indicating the relative positions of said tool carrying post and last mentioned slide.

2. A radius former comprising a base having a swivel support thereon, a first slide mounted for adjustment diametrically of said support, a second 50 slide mounted for transverse adjustment relative to said first slide, an upright post carried by one of said slides, means for supporting a tool on said post, a visual indicator on one of said slides, a cam on the other slide, and actuating means operatively associated with said cam and indicator for indicating the relative positions of said slides.

3. A radius former comprising a base having a swivel support thereon, a first slide mounted for adjustment diametrically of said support, a second 60 slide mounted for transverse adjustment relative to said first slide, an upright post carried by one of said slides, means for supporting a tool on said post, a visual indicator on one of said slides, a cam on the other slide, and a bell crank lever having one arm operative to actuate said indicator and the other arm in sliding engagement with said cam for displacement thereby to indicate on said indicator the relative positions of said slides.

4. A radius former comprising a base having a swivel support thereon, a first slide mounted for adjustment diametrically of said support, a second 70 slide mounted for transverse adjustment relative to said first slide, an upright post carried by one of said slides, means for supporting a tool

on said post, a visual indicator on one of said slides, a cam on the other slide having opposed inclined camming surfaces merging one into the other on a line intersecting the axis of rotation of said swivel support, and actuating means operably associated with said cam and indicator movable relative to said cam over said cam surfaces for positioning said indicator in accordance with the relative positions of said slides.

5. A radius former comprising a base having a swivel support thereon, a first slide mounted for adjustment diametrically of said support, a second slide mounted for transverse adjustment relative to said first slide, an upright post carried by one of said slides, means for supporting a tool on said post, a visual indicator on one of said slides, a cam on the other slide having opposed inclined camming surfaces merging one into the other on a line intersecting the axis of rotation of said swivel support, and a bell crank lever having one arm thereof operably associated with said indicator and the other arm extending into engagement with said cam for displacement by said cam surfaces in accordance with the relative positions of said slides.

6. A radius former comprising a base having a swivel support thereon, a first slide mounted for adjustment diametrically of said support, a second slide mounted for transverse adjustment relative to said first slide, a hollow upright post carried by said second slide, means for supporting a tool on said post, a visual indicator on said post, a cam on said first slide, and actuating means mounted on said second slide operably connected with said indicator through said post and displaceable by said cam in accordance with the relative positions of said slides.

7. A radius former comprising a base having a swivel support thereon, a first slide mounted for adjustment diametrically of said support, a second slide mounted for transverse adjustment relative to said first slide, a hollow upright post carried by said second slide, means for supporting a tool on said post, a visual indicator on said post, a cam mounted on said first slide, and a bell crank lever pivotally supported on said second slide, one arm of said bell crank lever being operably connected with said indicator through said post and the other arm thereof being in slidable engagement with said cam for displacement thereby in accordance with the relative positions of said slides.

8. A radius former comprising a base having a swivel support thereon, a first slide mounted for adjustment diametrically of said support, a second slide mounted for transverse adjustment relative to said first slide, a hollow upright post carried by said second slide, means for supporting a tool on said post, a visual indicator on said post, a cam mounted on said first slide, a bell crank lever pivotally supported on said second slide, one arm of said bell crank lever being operably connected with said indicator through said post and the other arm thereof being in slidable engagement with said cam for displacement thereby in accordance with the relative positions

of said slides, and a protective cap carried by said post slidable into and out of position for enclosing said lever.

9. A radius former comprising a base having a swivel support thereon, a first slide mounted for adjustment diametrically of said support, a second slide mounted for transverse adjustment relative to said first slide, a hollow upright post carried by said second slide, means for supporting a tool on said post, a visual indicator on said post, a cam on said first slide having opposed camming surfaces extending outwardly at an angle to each other merging centrally in a line intersecting the center of rotation of said swivel support, and a bell crank lever pivotally mounted on said second slide having one arm operably connected with said indicator through said post and the other arm having slidable engagement with said cam surfaces, whereby said cam surfaces will effect displacement of said bell crank lever in accordance with the relative positions of said slides.

10. A radius former comprising a base having a swivel support thereon, a first slide mounted for adjustment diametrically of said support, a second slide mounted for transverse adjustment relative to said first slide, means for supporting a tool on one of said slides, a visual indicator on said tool carrying slide, a cam on the other slide having opposed inclined camming surfaces merging one into the other on a line intersecting the axis of rotation of said swivel support, and actuating means operably associated with said cam and indicator movable relative to said cam over said cam surfaces for positioning said indicator in accordance with the relative positions of said slides.

11. A radius former comprising a base having a swivel support thereon, a first slide mounted for adjustment diametrically of said support, a second slide mounted for transverse adjustment relative to said first slide, means for supporting a tool on one of said slides, a visual indicator on said tool carrying slide, a cam on the other slide, and actuating means operably associated with said cam and indicator for indicating the relative positions of said slides.
